UNITED STATES PATENT OFFICE.

PETER RASMUS AAS, OF TRONDHJEM, NORWAY.

BITLESS BRIDLE.

1,315,357.

Specification of Letters Patent. Patented Sept. 9, 1919.

Application filed December 20, 1918. Serial No. 267,572.

To all whom it may concern:

Be it known that I, PETER RASMUS AAS, a citizen of Norway, residing at Trondhjem, Norway, have invented new and useful Improvements in Bitless Bridles, of which the following is a specification.

The present invention relates to bitless bridles of the kind in which the levers connected with the reins operate in such a manner as to pull together the nose-strap and the chin-strap and thereby to exert a pressure upon the nose-bone of the horse.

In the accompanying drawing Figure 1 is a side elevation of the bridle, Fig. 2 shows 15 on a greater scale a transverse section after the line 1—1 in Fig. 1 and Fig. 3 shows the bridle mounting with one part of the double rosette removed.

The mounting consists of two parts, 20 firstly of a downwardly directed lever —a— and secondly the double rosette —bb—. The lever —a— is provided with one or more holes (10—17) for the reins. Further this lever has a pin —1— for the nose strap —2— and a pin —3— for the chin strap —4—, these pins being placed diametrically on each side of a bolt or pin —5— around which bolt the lever is pivoted.

The pins 1 and 3 are suitably placed in a 30 plane perpendicular to the lever —a—, but of course they may be placed in an attitude somewhat out of the said plane.

The bolt —5— goes through the two 35 halves of the second part of the mounting, that is the double-rosette,—and is provided with a head —12— at one end and with a split pin —18— on the other end, thus securing the two parts of the double-rosette to each other in their center. The double- 40 rosette is provided with extensions —6— to which the check strap —7— is fastened through holes —13—, these extensions being connected with each other through a bolt —8—, around which the two parts of the 45 rosette may be pivoted when the bolt —5— is removed. In the nose-strap and the chin- strap are suitably either metal plates sewed in as shown at —14— on the chin-strap Fig. 3 or the whole end —15— of the strap may 50 be made of metal as shown on the nose-strap in the same figure, but these metal parts on the straps are of course not absolutely necessary. In all cases the straps or their metal parts are provided with oblong holes or 55 slots —16— by means of which the straps are hung on the pins —1— and —3— of

the lever —a—, these pins being provided with suitable heads.

The ends of the reins are fastened in the lower holes —10— of the lever —a—, it 60 being understood that such a mounting as hereby described is hung up in the check strap at either side of the horse's head.

When the reins are pulled, the lower part 65 of the lever —a— is moved in the direction of the arrow —10—, whereby one of the pins —1— is moved upward and the other one —3— is moved downward as indicated by the arrows —11—. The consequence is that the nose and chin straps —4— and 70 —2— in usual manner are pulled somewhat together so that a pressure is exerted on the very sensitive nose of the horse.

When it is not necessary to exert a very 75 large force upon the lever —a—, because the horse is easy to check, the reins may be attached in the upper hole —17— of each lever.

Having now described by invention, what I claim as new and desire to secure by Letters Patent is:

1. A bitless bridle comprising a double rosette, a lever pivoted to the rosettes, a chin strap and a nose strap connected to said lever, and a rein connected to the lever 85 in such manner that when a pull is exerted on the rein, the lever will cause the nose strap and chin strap to grip the nose of a horse.

2. A bitless bridle comprising a double 90 rosette, a lever pivoted to the rosettes, a chin strap and a nose strap connected to said lever at points diametrically opposite each other and upon opposite sides of the pivot, and means on said lever for adjustably receiving a rein.

3. A bitless bridle comprising a pair of spaced rosettes, a lever pivotally mounted between the rosettes, and means for connecting a chin strap and a nose strap to the 100 lever at opposite sides of the pivot point thereof.

4. A bitless bridle comprising a double rosette, a bolt extending transversely through said rosettes, a lever pivoted on the 105 bolt and disposed between the rosettes, extensions formed on the rosettes and formed with openings to receive a check strap, and means for connecting straps to the lever at opposite points and upon opposite sides of 110 the bolt.

5. A bitless bridle comprising a double

rosette, a bolt extending transversely through said rosette, a lever pivoted on the bolt and disposed between the rosettes, extensions formed on the rosettes and formed 5 with openings to receive a check strap, a pivot pin extending through said extensions and about which the rosettes swing when the bolt is removed, and means for connect-

ing straps to the lever at opposite points and upon opposite sides of the bolt. 10

In testimony whereof I have signed my name to this specification.

PETER RASMUS AAS.
